SHADE HOLDER FOR PORTABLE ELECTRIC LAMPS

Filed Aug. 20, 1929

UNITED STATES PATENT OFFICE

MICHAEL B. BOWEN, OF DECATUR, ILLINOIS, ASSIGNOR TO FARIES MANUFACTURING COMPANY, OF DECATUR, ILLINOIS, A CORPORATION OF ILLINOIS

SHADE HOLDER FOR PORTABLE ELECTRIC LAMPS

Application filed August 20, 1929. Serial No. 387,190.

My invention relates more particularly to portable desk lamps which have an adjustable arm which carries the lighting element, and in which one side of the shade is provided with a slot which will span the arm, this slot usually being provided with some sort of means for conveniently changing the shade.

As is well known, these shades are usually formed of glass, and the glass is very irregular, so that it becomes difficult to attach the securing means because of the holes getting out of register, and if the holes are placed properly in register then the holder fails to clamp the shade with a sufficient degree of firmness.

My invention has for its objects, to provide a shade holder which under all circumstances will hold the shade firmly and in horizontal position; and to provide clamping means which will clamp it, regardless of the irregularities of the shade, in such a manner that it will be securely locked in position, yet the locking means will not change the shade nor twist it out of the horizontal position which it should properly occupy.

My means for accomplishing the foregoing objects may be more readily understood by reference to the accompanying drawings, which are hereto annexed and are a part of this specification, in which—

Fig. 1 is a side elevation of a portable desk lamp equipped with my improved shade holder;

Fig. 2 is a fragmentary detail view of the shade holder, showing one of the means for locking the shade in position;

Fig. 3 is a cross-section, taken on the line 3—3 in Fig. 2;

Fig. 4 is a detail elevation of the shade holder; and

Fig. 5 is a cross-section taken on the line 5—5 in Fig. 4.

Similar reference numerals refer to simi-

lar parts throughout the entire description.

In the drawings is shown a desk lamp, having a base 1, standard 2, adjustable arm 3, and shade 4. The shade 4 is shown equipped with my improved holder, which, as more clearly seen in the detail views, comprises a pair of plates 5 and 6, and an intermediate plate 7.

The plate 6 is provided with a peripheral flange 8, which is adapted to contact the shade 4, and the edge of the flange 8 is formed to fit the configuration of the shade 4, so as to give a neatly finished appearance to the device when attached. The central portion of the plate 6 is cut away to form an arch, the vertical edges of which are formed into V-shaped tongues 9 which are adapted to form guides. On the arm 3 I mount a guide-plate 10, the edges of which are formed with a V-shaped groove 11 which is fitted to and coincides with the V-shaped tongues 9 on the plate 6. At the bottom of the plate 6, and on each side of the arch-like opening therein, I provide a flat flange 12, upon which rests the lower edge 13 of the shade 4 at each side of a slot formed therein which is adapted to span the arm 3, thereby insuring the shade 4 being held in horizontal position. In the plate 6 I provide a pair of slotted apertures 14 for the passage of screws 15, which are adapted to register with threaded apertures 16 formed in the plate 5. The screws 15 pass through apertures 17 formed in the intermediate plate 7.

The intermediate plate 7, having an arcuate flange 19 on its upper edge, is mounted between the plates 5 and 6. This plate 7 also has a central arch-like opening, corresponding in shape to the arch-like openings formed in plates 5 and 6.

The plate 5 is formed with a curved shoulder 18, adapted to fit the curvature of the shade 4 adjacent its slot. Plate 5 also has a pair of threaded openings 16, adapted

to receive the ends of screws 15. In the lower part of this plate 5 I also provide a pair of slotted openings 20, to register with a pair of apertures 21 formed in plate 6. 5 Screws 22 are adapted to pass through these apertures 21 and slotted openings 20 and enter threaded apertures 23 formed eccentrically in serrated-edges camshaped members 24. Plate 5 also has detents 25 adjacent 10 its lower edge, said detents 25 being struck up from the metal forming the plate 5, immediately below the slotted openings 20.

The device is assembled as follows:

The plate 6 is placed on the outside of the shade 4, with its peripheral flange 8 contacting the shade 4. The intermediate plate 7 is then placed in position, its arcuate flange 19 being adapted to engage the curvature at the top of the slot formed in the shade 4. Plate 5 is then placed in position, and the screws 15 are passed through the slotted apertures 14 in plate 6, apertures 17 in intermediate plate 7, and enter the threaded apertures 16 in plate 5. Screws 22 are then passed through apertures 21 in plate 6 and slotted openings 20 in plate 5, and caused to engage the threaded apertures 23 in the cam-shaped members 24.

Owing to the slotted apertures 14 in plate 6, it is possible to slide the intermediate plate 7 up against the top of the slot formed in the shade 4, when by tightening the screws 15 the intermediate plate 7 and the shade 4 are firmly held. The pair of slots 20 in plate 6 provide for compensating any irregularities in the shape or configuration of the shade 4. When this adjustment is made, the serrated-edged cams 24 are tightened by means of the screws 22, 30 the serrations on the cams 24 engage the struck-up detents 25, and this has the effect of locking the screws 22, and in turn the plates 5 and 6, firmly in position, so that they will not loosen readily, regardless of 40 how many times the shade 4 may be changed.

Having described my invention, what I regard as new, and desire to secure by Letters Patent of the United States, is:

1. In a portable desk lamp, having a shade provided with a slot, a shade holder mounted in said slot, said holder comprising front and rear plates having arch-like openings formed therein, an intermediate plate having an arch-like opening and having its upper edge flanged in arcuate form, registering apertures in said plates, upper and lower screws to hold said plates together, an arch-shaped guide-plate mounted on said lamp, having a V-shaped groove on 50 its top and side edges, parallel V-shaped tongues formed on the vertical edges of the arch-like openings in the front and rear plates, adapted to fit the V-shaped groove on said guide-plate, inwardly extending 55 apertures in the front and rear plates, upper and lower screws to hold said plates together, an arch-shaped guide-plate mounted on said lamp, having a V-shaped groove on its top and side edges, parallel V-shaped tongues formed on the vertical edges of the arch-like openings in the front and rear plates, adapted to fit the V-shaped groove on 60 said guide-plate, inwardly extending apertures in the front and rear plates, upper and lower screws to hold said plates together, an arch-shaped guide-plate mounted on said lamp, having a V-shaped groove on its top and side edges, parallel V-shaped tongues formed on the vertical edges of the arch-like openings in the front and rear plates, adapted to fit the V-shaped groove on 65 said guide-plate, inwardly extending apertures in the front and rear plates, upper and lower screws to hold said plates together, an arch-shaped guide-plate mounted on said lamp,

plate at either side of the arch-like opening, screw-threaded eccentric cams mounted on said lower screws, serrations on the edges of said cams, and detents on said rear plate which engage the serrated edges of said cams.

2. In a portable desk lamp having a shade provided with a slot, a shade holder mounted in said slot, said holder comprising front and rear plates having arch-like openings formed therein, a peripheral flange on said front plate which conforms to the configuration of the shade, an intermediate plate having an arch-like opening and having its upper edge flanged in arcuate form, registering apertures in said plates, upper and lower screws to hold said plates together, an arch-shaped guide-plate mounted on said lamp, having a V-shaped groove on its top and side edges, parallel V-shaped tongues formed on the vertical edges of the arch-like openings in the front and rear plates, adapted to fit the V-shaped groove on said guide-plate, inwardly-extending shoulders on the lower edge of the front plate at either side of the arch-like opening, screw-threaded eccentric cams mounted on said lower screws, serrations on the edges of said cams, and detents on said rear plate which engage the serrated edges of said cams.

3. In a portable desk lamp having a shade provided with a slot, a shade holder mounted in said slot, said holder comprising front and rear plates having arch-like openings formed therein, an intermediate plate having an arch-like opening and having its upper edge flanged in arcuate form, registering apertures in said plates, the upper apertures in the front plate and the lower apertures in the rear plate being slotted, upper and lower screws to hold said plates together, an arch-shaped guide-plate mounted on said lamp, having a V-shaped groove on its top and lower edges, parallel V-shaped tongues formed on the vertical edges of the arch-like openings in the front and rear plates, adapted to fit the V-shaped groove on said guide-plate, inwardly-extending shoulders on the lower edge of the front plate at either side of the arch-like opening,

100 slotted, upper and lower screws to hold said plates together, an arch-shaped guide-plate mounted on said lamp, having a V-shaped groove on its top and lower edges, parallel V-shaped tongues formed on the vertical edges of the arch-like openings in the front and rear plates, adapted to fit the V-shaped groove on said guide-plate, inwardly-extending shoulders on the lower edge of the front plate at either side of the arch-like opening, screw-threaded eccentric cams mounted on said lower screws, serrations on the edges of said cams, and detents on said rear plate which engage the serrated edges of said cams.

4. In a portable desk lamp having a shade provided with a slot, a shade holder mounted in said slot, said holder comprising front and rear plates having arch-like openings formed therein, means mounted intermediate said plates which furnishes additional support for the shade, registering apertures in said plates, upper and lower screws to hold said plates together, an arch-shaped guide-plate mounted on said lamp,

having a V-shaped groove on its top and side edges, parallel V-shaped tongues formed on the vertical edges of the arch-like openings in the front and rear plates, adapted to fit the V-shaped groove on said guide-
5 plate, inwardly-extending shoulders on the lower edge of the front plate at either side of the arch-like opening, screw-threaded eccentric cams mounted on said lower screws, serrations on the edges of said cams, and
10 detents on said rear plate which engage the serrated edges of said cams.
